United States Patent Office.

WILLIAM MADDUX, OF RIPLEY, OHIO.

Design No. 3,519, dated June 1, 1869.

DESIGN FOR A TRADE-MARK.

The Schedule referred to in these Letters Patent and making part of the same.

To all whom it may concern:

Be it known that I, WILLIAM MADDUX, of Ripley, in the county of Brown, and in the State of Ohio, have invented a certain new and useful Design for Label; and do hereby declare that the following is a full, clear, and exact description thereof, reference being had to the accompanying drawings, and to the letters of reference marked thereon, making a part of this specification.

The nature of my invention consists in the combination of certain letters in such a manner as to form a label, to be used as a trade-mark.

There are four of these letters, J, T, A, and R, which are intertwined, as shown in the accompany-

ing drawing, in such a manner as to form a monogram, which I desire to use as a design for a label.

Having thus described my invention,

What I claim as my invention, and desire to secure by Letters Patent, is—

The above-described design for labels, as herein set forth and described.

In testimony that I claim the foregoing, I have hereunto set my hand, this 4th day of May, 1869.

WM. MADDUX.
